ABSTRACT OF THE DISCLOSURE

A high-voltage rectifier for the supply of heavy currents including an arrangement of an anode within a hollow cathode and a source of a magnetic field having lines of force which intersect the cathode twice without intersecting the anode.

This invention relates to electrical devices intended for converting high voltage currents and, more particularly, relates to a method of rectifying high-voltage heavy currents and to a device for the realization of said method, i.e. an arc valve with a cold cathode.

Certain essential disadvantages are inherent in known power mercury-arc rectifiers. While in many cases there is no need in the starting phase for adjustment of such rectifiers, special ignition devices are nevertheless required for the operation. In excitrons, for instance, such an ignition device is an excitation arc on auxiliary anodes, said arc consuming a considerable amount of electric power. Moreover, the excitation arc acting during an idle half-cycle reduces the back voltage of the excitron. In the ignitron, an ignition device is an igniter usually made of semiconductor materials. The greatly variable characteristics of the igniter affect the normal rectifier operation. In practice, the service-life of an ignitron is entirely dependent upon the service-life of the igniter. Moreover, it can be said in general that ignition devices are the most complex and unreliable elements of mercury-arc rectifiers.

Another disadvantage of the mercury-arc rectifier is found in the mercury-pool cathode. While it offers a number of merits, it creates certain difficulties in the manufacturing of rectifiers, requires the introduction of auxiliary screens into the rectifier chamber and makes rectifiers greatly responsive to temperature. That is why the temperature of the operating rectifiers should be kept with the aid of a temperature controlling system at a given level within the close limits thereof. Such system consumes large amounts of electric power. With ignitrons operating in pulsing circuits, the pool cathode limits the rectifier current-carrying capacity to a value not exceeding 10 ka.

A glow-discharge device of the Phillips ion gage type was proposed to be used as a rectifier with a cold cathode, operating without preliminary ignition, said device comprising a cathode, a target and a ring anode, all placed in a magnetic field. This system of electrodes placed in a magnetic field has different discharge starting potentials with the reversing of the anode polarity. The use of such devices is greatly limited, however, by some undesirable features inherent in the glow-discharge, namely by a considerable voltage drop during the conductive half cycle and a low magnitude of the rectified current, of the order of 10 milliamperes.

An object of the present invention is to provide a method for rectification of high voltage alternating currents.

Another object of the invention is to provide an arc valve with a cold cathode capable of rectifying high voltage heavy currents (as high as some hundreds of amperes) without the use of an ignition device.

5 With the foregoing and other objects in view, the present invention consists of a novel device, i.e. an arc valve with a cold cathode in a magnetic field, and a method of rectifying alternating currents.

The method of the electric current rectification and the principle of operation of the proposed arc valve in a magnetic field are based on the sharp difference between the discharge starting potentials with the reverse polarity of electrodes forming a gas-discharge gap in a magnetic field, provided certain conditions are available. 10 15 These conditions arise if the shape of the electrodes and the configuration of the magnetic field are so selected that part of the magnetic lines of force in the discharge gap twice intersects the cathode without passing through the anode. An alternate condition providing for the difference 20 in starting potentials is utilized in the known glow-discharge devices of the Phillips ion gage type.

The same phenomenon can be employed to initiate the low gas pressure arc discharge. If during the conductive half cycle the potential of the anode attains the 25 value of the starting potential, the discharge immediately takes the form of an arc with a low drop of voltage of some tens of volts, characteristic for this form. When the conducting half-cycle is over and the polarity of the electrodes has changed for the reversed one, an arc 30 discharge is not likely to occur.

The arc valve employing a magnetic field and operating in the way described hereinbefore comprises a metal cylindrical chamber serving as a hollow cathode with a flat anode disposed inside said chamber. The arc valve 35 is placed in the magnetic field of a coaxial solenoid so that the above mentioned condition concerning the dependence of the discharge starting potential upon the polarity of the electrodes can be realized. The arc valve is capable of rectifying alternating current without an 40 ignition device exciting an arc with the anode potentials being comparatively low (500-1000 v.) and depending on the magnetizing force, pressure, kind of gas and the shape and material of the cathode, said rectifier withstanding at the same time a considerable back voltage (of the order of 10 kv.)

45 For operation in pulsing circuits, the valve may be provided with an ignition device. Decreasing the magnetic field, it is possible to obtain such conditions when the arc discharge does not appear even with the anode being positive. In this case an insignificant additional ionization 50 will bring to the breakdown of the discharge chamber of the arc valve. The additional ionization may be brought about by means of a small hot tungsten cathode or by a low power boosting discharge in an auxiliary chamber which is located under the main chamber and is communicating with the latter through several narrow-bore 55 passages, the auxiliary chamber being placed in the magnetic field of said solenoid.

Other objects and advantages of the present invention 60 will be more apparent from the following description taken in conjunction with the accompanying drawings, wherein:

FIG. 1 illustrates the arrangement of electrodes in a magnetic field;

FIG. 2 graphically illustrates the starting potential-pressure dependence for the electrodes arrangement of FIG. 1;

FIG. 3 is a cross section of an arc valve with the cold cathode placed in a magnetic field;

FIG. 4 illustrates an arc valve with the cold cathode 65 placed in a magnetic field and with an auxiliary ignition chamber; and

FIG. 5 illustrates an arc valve with the cold cathode placed in a magnetic field with a hot ignition filament.

The method proposed herein for alternating current rectification by means of an arc discharge gap between cold electrodes placed in a magnetic field is based on a fact that the magnetic field under certain conditions considerably reduces discharge starting potentials with either polarity of the electrodes. If a certain system of electrodes (FIG. 1) is placed in a magnetic field so that part of the magnetic lines (lines I and II; FIG. 1) of force twice intersects one of the electrodes, a cylindrical cathode made, for instance, as a cylindrical chamber without passing through the other—the anode made, for instance, as a disc-shaped electrode, then, with the anode being positive, a potential well for the electrons will appear in the space between the electrodes, particularly in the zone of the magnetic lines of force marked with a circle (zone III, FIG. 1). In fact, the magnetic field prevents the electrons from escaping this zone and reaching the anode, and the electric field does not permit them to come to the cathode. The electrons perform an oscillatory motion along the magnetic lines of force and drift in the intersecting electric and magnetic fields about the axis of the system of electrodes. Moving in this zone for a sufficiently long period of time, the electrons ionize the gas even under low pressure conditions, provided that the length of their mean free path is much greater than that of the gap between the electrodes. As a result, with the anode being positive, the discharge starting voltage sharply drops. When the anode is negative, the electrons rapidly leave the space between the electrodes for the positive cathode. In this case the electric strength of the gap is sufficiently high and is defined by the left branch of the Paschen curve. FIG. 2 illustrates the dependence of the starting potential in the system of electrodes as in FIG. 1 upon the pressure (for the air) at various values of the magnetic field H . The continuous lines (for $H_1=160$ oersteds, $H_2=190$ oersteds and $H_3=220$ oersteds) correspond to potentials of the positive anode and the dotted line to that of the negative anode respectively. With the anode being negative, a magnetic field of several hundred oersteds is of no influence upon the electric strength of the gap. As seen from FIG. 2, the value of the potential at which the glow discharge occurs depends upon the magnetic field and upon the pressure. Besides, it also depends upon the configuration of the magnetic field, the shape and material of the cathode and on the kind of gas.

The peculiar feature of the method to be claimed is that of the use of an arc valve with a low drop of voltage. Though the chosen forms of the electrodes and configuration of the magnetic field are not the only possible embodiments of the invention, they still provide a relatively low discharge starting potential during the conductive half cycle with the minimum (of the order of 10–20 oersteds) magnetic field within the zone of the anode. It is just the last circumstances that facilitate a quick and practically instantaneous glow-to-arc transition even at currents of about 10 a.

Since this arc discharge can be effected at a low gas pressure, the charged particles, after the discharge is over and the polarity of the electrodes has been changed, recombine on the electrodes. The space between the electrodes becomes quickly de-ionized, the electric strength is restored and the arc-back does not appear. The pressure after passing of the current pulse does not increase, except for a relatively short process of aging. Moreover, a reduction of the gas pressure has been observed in the discharge chamber due to the passage of the current pulse.

The invention will now be described in connection with a possible embodiment of the device for realization of said method.

Cylindrical aluminum chamber 1 (FIG. 3) serving as a hollow cathode of an arc valve is sealed on base 2 by

means of rubber washer 3. Copper anode 5 cooled by water supplied through pipes 4a is inserted in the chamber via insulator 4. The magnetic field is generated by solenoid 6 located coaxially under the base of the valve.

5 The cathode is cooled by running water delivered to jacket 7. The gas is evacuated from the chamber through branch pipe 8. The pressure of gas, say air or hydrogen, is set by means of an adjustable needle valve through pipe 9. The pressure is measured by thermocouple pressure gage 10.

10 For the operation of the arc valve in pulsing circuits, the apparatus is provided with an ignition device. A modification of the valve with an auxiliary discharge serving as an ignition device is shown in FIG. 4. Auxiliary ignition chamber 11 is positioned under the main chamber 1 in the magnetic field of solenoid 6 and communicates with the latter through narrow passage 12. Ring anode 13 is placed inside the ignition chamber, said anode receiving the positive trigger pulse. To facilitate the booster discharge, the gas pressure in the ignition chamber is set 15 a little higher due to the direct delivery of gas into said chamber.

15 FIG. 5 illustrates another modification of the arc valve design provided with an ignition device made as a 25 miniaturized hot cathode. A tungsten filament 0.3 mm. thick insulated from the chamber is mounted eccentrically in base 2 of the valve. The recess in which hot ignition cathode 14 is positioned is screened from the main discharge chamber by metal grid 15. The filament is fed 30 with a fixed positive bias and at the moment of ignition it is fed with a negative trigger pulse.

30 In the steady process of the rectification of industrial frequency currents the valve operates in the pressure range equal to $(1 \text{ to } 10) \times 10^{-3}$ mm. Hg. The magnetic field in the center of solenoid 6 is approximately 100 oersteds and in the zone of anode 5 it drops to 10–20 oersteds. The peak value of the rectified industrial current is as high as 1000 a.

35 If the valve is cut into a choke-coil shorting circuit (crowbar) under the same pressure and magnetic field conditions, it starts automatically, when the voltage of inductance becomes positive, resulting in currents of the order of 50 ka. and more with the pulse duration being 40 10 milliseconds.

40 When the ignition occurs under the same pressure conditions but with a lower intensity of the magnetic field, the valve during the pulse operation can operate for an inductive load in a capacitor discharge circuit. If the pulse duration equals 1 millisecond, the valve retains the 45 property of unilateral conductivity with the peak currents 50 ka. and more and the voltage up to 10 kv. The pulse frequency in this duty is equal to several cycles per second. During single switchings of the valve the unilateral current conductivity thereof was noted to be rising up 55 to 100 ka.

55 While the present invention has been described in connection with the preferred embodiment thereof, it will be understood by those skilled in the art that changes and modifications may be made without departing from the 60 spirit and scope of the invention, and accordingly, all such changes and modifications which fall within the true spirit and scope of this invention are intended to be covered in the appended claims.

65 What is claimed is:

65 1. A high-voltage rectifier adapted for supplying heavy currents and comprising a metal envelope defining a chamber and including a cold hollow cathode, an anode inside said chamber, and means to generate a magnetic field in said chamber such that magnetic lines of forces 70 intersect the cathode twice without passing through the anode.

70 2. A rectifier as claimed in claim 1, wherein the envelope is cylindrical and the said means is a solenoid coaxial with the envelope.

75 3. A rectifier as claimed in claim 2, wherein the anode

is symmetrically disposed within the chamber at the top of the latter and the solenoid is located outside of and below the envelope.

4. A rectifier as claimed in claim 3 comprising auxiliary ignition means below said envelope and encircled by said solenoid.

5. A rectifier as claimed in claim 4, wherein said auxiliary ignition means is in communication with said chamber and includes a ring electrode supported on said envelope.

6. A rectifier as claimed in claim 3, comprising auxiliary ignition means within said chamber.

7. A rectifier as claimed in claim 6, wherein the envelope is provided with a recess at the bottom thereof to accommodate said auxiliary ignition means which includes a hot filament in the recess and a metal grid shielding the filament.

8. A rectifier as claimed in claim 3, wherein said anode is hollow, comprising means to supply a cooling medium into said anode and means to supply a cooling medium around said cathode, said rectifier further including means

to introduce a gas at controllable pressure into said cathode.

9. A rectifier as claimed in claim 8, wherein said envelope includes a cylindrical aluminum structure constituting the cathode, a disc-like base on which the cylindrical aluminum structure is supported, and a washer between the base and said structure.
